UNITED STATES PATENT OFFICE.

NORMAN D. BISHOP, OF LOS ANGELES, CALIFORNIA.

DESIGN FOR A COVERING FOR ELECTRIC-LAMP SOCKETS.

43,515.

Specification for Design.

Patented Feb. 11, 1913.

Application filed October 21, 1912. Serial No. 727,089. Term of patent 7 years.

To all whom it may concern:

Be it known that I, NORMAN D. BISHOP, a citizen of the United States of America, residing at Los Angeles, in the county of Los Angeles, State of California, have invented a certain new, original, and ornamental Design for a Covering for Electric-Lamp Sockets, of which the following is a specification, reference being had to the accompanying drawings, forming part hereof.

In the drawings, Figure 1 is a plan view of the covering for electric lamp socket showing my new design; Fig. 2 is a perspective view of the same, and Fig. 3 is an elevational view of the same mounted on a

lamp socket which is indicated by dotted lines.

I claim:

The ornamental design for a covering for electric lamp socket, as shown.

In testimony whereof, I have signed my name to this specification in the presence of two subscribing witnesses at Los Angeles, county of Los Angeles, State of California, this 19th day of September, A. D. 1912.

NORMAN D. BISHOP.
